ROYAL J. WRIGHT, OF SPRINGFIELD, MASSACHUSETTS, ASSIGNOR TO DURABILT CORSET COMPANY, OF SPRINGFIELD, MASSACHUSETTS, A CORPORATION OF MASSACHUSETTS.

LACING-FLAP FOR CORSETS.

1,355,207.

Specification of Letters Patent.

Patented Oct. 12, 1920.

Application filed August 9, 1919. Serial No. 316,365.

To all whom it may concern:

Be it known that I, ROYAL J. WRIGHT, of Springfield, county of Hampden, and Commonwealth of Massachusetts, a citizen 5 of the United States of America, have invented certain new and useful Improvements in Lacing-Flaps for Corsets, of which the following is a specification.

This invention relates to improvements in 10 lacing flaps for corsets. An object of the invention is to provide a corset in which a flap member is located between the lacing edges of the corset that are drawn together with the lacing strings. This member is 15 provided with eyelets through which pass the lacing. The flap member itself is also provided with eyelets to receive the strands of the lacing strings which pass through the eyelets of the corsets.

20 A further object of the invention is to so provide a flap member that will always and automatically close the opening between the lacing edges of the corset when the lacing is operated to draw the corset together over the flap member.

Referring to the drawings:

Figure 1 is a front elevational view showing the corset closed, that is to say, with the lacing strings drawn tight for holding the 30 edges substantially parallel to each other.

Fig. 2 is a detail view showing the lacing flap spanning the space between the open front edges of the corset.

Fig. 3 is a detail perspective view of the 35 lacing flap showing the center strip thereof, in which is located the eyelets, and the center strip raised slightly, and

Fig. 4 is a transverse sectional view on the line 4—4 of Fig. 1, showing the manner 40 of passing the lacing strings through the flap member and the adjacent side members of the corset.

Referring to the drawings in detail:—

1 and 2 designate the side members of the 45 corset. The usual stays are indicated at 3 and 4; the clasps at 5 and 6. The insert flap member is shown in detail in Fig. 3. It comprises three flexible strips indicated at 7, 8, and 9. These are connected together 50 at their extreme ends by means of the binding tapes 10 and 11. The center member 8, as shown in Fig. 3, is formed with the eyelets 12. It will be noticed that the center member is only connected to the members 7 and 9 by means of the binding tapes

at its ends, and the member 8 overlaps the members 7 and 9. The eyelets in the oppositely located lacing edges of the garment are indicated at 13 and 14. The flap member is preferably provided with stiffening 60 ribs or stays similar to those in the body of the corset. The lacings which pass through the eyelets 12, 13, and 14 are indicated at 15, and 16. These lacings represent one continuous piece, the middle point 65 of which is indicated at 17. From this point one half of its length passes to the left, as shown by the strand 18, then upward through the eyelet 19, then forward by means of the strand 20, then downward 70 through the eyelet 21 of the center piece 8, and then across as indicated at 22 and upward through the eyelet 23, then forward as indicated at 24, downward through the eyelet 25, to the left by the strand 26, upward 75 through the eyelet 27, and the loose folded continuous end portion 28, 29, which is continued as indicated by the dotted lines to the strand 30; then downward through the eyelet 31, strand 32, and eyelet 33, and 80 then continuously in an over and over direction and through the eyelets in the center member and side member until the loose end 34 is reached. The same manner of lacing on the other side starts from the 85 middle point 17 and proceeding in the same manner on the right side of the view shown in the Fig. 2 and proceeding in an over and over direction until the end 35 is reached. These ends 34 and 35 are tied together. The 90 loose folded strands 28 and 30 are long enough to pass around the waist of the wearer and hold the garment in place.

As indicated in Fig. 2 the flap member is shown as nearly filling the space between 95 the opposite edges of the corset, while in Fig. 1 the edges of the corset are drawn nearly together, and the flap member is located back of the adjacent members at their lacing edges, as indicated by dotted lines 100 at 36.

One important feature of the invention is that when the lacings are drawn by the wearer through the eyelets, the flap member will not pucker up, but will lie flat on 105 the strands of the lacings in parallel relation to the side members 1 and 2 of the corset. If it is desired to hold the side members 1 and 2 of the corset open as shown in Fig. 2, the flap spans the space as indi- 110

cated. It should also be observed that when the loose strands 28 and 30 are drawn the two side members of the corset are simultaneously drawn toward the center and at 5 equal distances so that the space over the flap member is symmetrically arranged.

From this construction it will be seen that I have provided a member that can be readily detached from the parts of a front or 10 back laced corset, if desired, and which can be readily attached as desired if it is not necessary to use this flap member.

What I claim is:

In combination with a corset having eye- 15 leted lacing edges, a flap member adapted to be placed behind said lacing edges and

comprising two parallel strips of flexible fabric spaced apart and provided with stays, a third strip also stayed over-lying said strips and the space therebetween, a 20 permanent connection between said strips at the upper and lower ends only, a single row of eyelets in the center of said third strip extending the length of said strip, and a single lacing cord engaging the eyelets in the strip and in the lacing edges of the corset in such manner that said edges may be simultaneously drawn together substantially into contact and over the flap member. 25

ROYAL J. WRIGHT.
